CLAIM

The ornamental design for a light pole as shown and described.

DESCRIPTION

FIG. 1 is a front, right-side, and top perspective view of a light pole showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear, right-side, and top perspective view thereof;

FIG. 9 is a front, right-side, and bottom perspective view thereof; and,

FIG. 10 is a front, left-side, and bottom perspective view thereof.

The dashed broken lines depict portions of the light pole that form no part of the claimed design.
